CLAIM

The ornamental design for a hat storage container, as shown and described.

DESCRIPTION

The patent or application file contains at least one drawing executed in color. Copies of this patent or patent application publication with color drawing(s) will be provided by the Office upon request and payment of the necessary fee.

1. Hat storage container

1.1 is a top and side perspective view shown in a closed configuration.

1.2 is a top, side and front perspective view of 1.1.

1.3 is a front elevation view of 1.1.

1.4 is an opposite side elevation view thereof, shown in an open configuration.

1.5 is a top, side and front perspective view of 1.4.

1.6 is a top, opposite side and rear perspective view of 1.4, with hat stop shown in an alternate position.

1.7 is a top, opposite side and rear perspective view of 1.1.

1.8 is a top plan view of 1.1.

The present invention/industrial design is a hat storage container for storing and transporting a plurality of hats; the present invention features 3 constituent parts: lid portion, base portion and hat stop portion; the lid portion and the base portion are interconnected by a hinge to form a clamshell case; the hat stop portion can be interconnected with the base

(Continued)

portion; whilst interconnected, the hat stop portion can be adjusted to a forward or rear position, as required; the hat stop portion is removable.
